APPARATUS FOR THE REMOVAL OF CUTTINGS FROM DRILL HOLES

Allan S. Richardson and William C. Williamson,
Butte, Mont.

Application March 6, 1952, Serial No. 275,042

1 Claim. (Cl. 255—50)

This invention relates to improved apparatus for the removal of rock cuttings from holes being drilled dry in the earth. Essentially the apparatus comprises a combination of means to introduce compressed air into the hole being drilled, to blow the cuttings up the hole, a hood surrounding the mouth of the hole, and suction means connected to the hood to draw the stream of air-borne cuttings away from the mouth of the hole and thus to remove the dust and cuttings from the immediate vicinity of the drilling operation. The invention provides improvements in the form of a rock trap to separate large rock cuttings out of the air stream and a dust collector wherein the fine rock cuttings can be collected in a water slurry.

It is advantageous in many situations to drill holes in rock dry rather than with the use of water or other drilling liquid. Particularly in the case of shallow vertical holes, such as those drilled for the placing of explosives, it is generally easier to remove rock cuttings from a dry-drilled hole by means such as a blast of compressed air than it is to remove such cuttings when compacted into a mud by wet drilling. In some localities dry drilling may be necessitated by a lack of an adequate supply of water. Also during winter months wet drilling may be very troublesome or impractical due to the formation of ice.

It has been proposed heretofore to use compressed air for the removal of dust and cuttings from dry-drilled holes. Compressed air is ordinarily available at drilling sites since it must be supplied for the operation of the pneumatic drills usually employed. It is piped to the bottom of the hole and blows the cuttings up to the mouth of the hole and out into the atmosphere. Whenever the compressed air is admitted to the hole a cloud of dust emerges from the mouth of the hole. This dust constitutes a menace to the health of the operators and an obstacle to the safe operation of the drilling machine. The present invention eliminates the dust hazard and accomplishes the continuous removal and disposal of rock dust and cuttings by compressed air.

The apparatus of the invention comprises essentially a combination of means to introduce compressed air into a drill hole, a hood surrounding the mouth of the hole to confine the dust and cuttings blown up out of the hole by the compressed air, and suction means to draw the air-borne cuttings through the hood and away from the mouth of the drill hole. A rock trap in the form of a chamber that is of large internal cross-sectional area relative to the drill hole and hood is mounted in close proximity to the hood and is connected thereto by a short length of conduit which is small in cross-sectional area relative to the trap. The larger pieces of rock and rock cuttings blown out the hole are collected in this trap before they can enter the suction device and either clog it or damage it. Advantageously, the air suction means is a venturi tube ejector which is operated by a stream of compressed air directed into its throat through a nozzle pipe mounted in the venturi tube a short distance up-

2

stream from its throat. To insure complete elimination of any dust nuisance, a dust collecting chamber may be provided at the discharge of the venturi tube or other suction device. The dust collecting chamber comprises a series of closely spaced contactor plates, and a spray nozzle mounted upstream from them for delivering a film of water to their surfaces. Fine cuttings and rock dust discharged from the venturi impinge on the water film on the plates and thus collect in an aqueous slurry which is readily disposed of.

An advantageous embodiment of the invention is shown in the accompanying drawings, in which

Fig. 1 is an elevation partly in section of the new apparatus for removing dust and cuttings from drill holes

Fig. 2 is a plan of the hood surrounding the mouth of the drill hole, taken substantially on the line 2—2 of Fig. 1;

Fig. 3 is an elevation in section of the venturi tube and the nozzle pipe that operates it; and

Fig. 4 is an elevation in section of the dust collecting chamber at the discharge end of the venturi tube.

As shown in Fig. 1, the complete apparatus as installed for operation comprises some five main components arranged in the following order: a compressed air delivery pipe 5, a hood 6, a dust trap 7, a venturi ejector tube 8, and a dust collecting chamber 9. The compressed air delivery pipe 5 enters a drill hole 10 at its mouth and passes down to the bottom where the drill bit 11 mounted on a drill rod 12 and driven by drilling machine 13 is cutting through the earth. The stream of compressed air from the pipe 5 blows rock dust and cuttings up around the drill rod 12 to the mouth of the drill hole, which opens into the interior of the hood 6. The amount of compressed air supplied should of course be sufficient to blow all cuttings out of the hole continuously, as fast as they are produced by the drill bit. If a hollow drill pipe is used in place of the drill rod 12 to carry the drill bit 11, such drill pipe may be used also as the compressed air delivery pipe in place of the pipe 5.

The hood 6 is a conical enclosure surrounding the mouth of the drill hole and apertured by the provision of a slot 14 to enable the air pipe 5 and the drill rod 12 to enter the drill hole. A hollow stem 15 attached to the bottom of the hood 6 extends for a foot or so down into the upper end or mouth of the drill hole 10, to locate the hood properly with respect to the hole and to secure it in place. However, the stem 15 is not essential to successful use of the apparatus—a hood without any such stem has in fact been employed successfully.

A short horizontal conduit 16 connects the hood 6 with the dust trap 7. The dust trap 7 comprises a chamber of large cross-sectional area relative to the hood 6 and the drill hole 10. It is conveniently made of sheet metal welded or riveted into the form of a rectangular or cylindrical box, and is mounted in close proximity to the hood 6. The conduit 16 connects with the inlet side of the trap 7 in off-center relation therewith, at a point near its bottom, and another horizontal conduit 17 (which leads away from the upper portion of the dust trap and provides for connection through a flexible hose 18 with the venturi tube ejector 8) connects with the outlet side of the trap 7 in off-center relation therewith, at a point near its top. The conduit 17 extends well into the upper portion of the dust trap 7, and its open inner end 19, which is situated inside the dust trap 7, is cut away at an angle of approximately 45° so that it faces away from the end of the conduit 16 where the latter opens into the interior of the trap chamber.

Dust and cuttings blown up the drill hole into hood 6 pass through the horizontal conduit 16 into the lower portion of dust trap chamber 7. Since the velocity of air movement from the hood is preferably high, some rather

large fragments of rock are carried from the hole through the duct 16 and, but for the trap 7, would find their way into the ejector tube 8 and might either damage it or clog it. The trap 7, however, provides a chamber wherein the air velocity is relatively low and in which the larger and heavier rock fragments and cuttings can settle out. The off-center and non-coaxial relation of the connections of the conduits 16 and 17 to the trap insure that such material does not simply pass through the trap. The trap may be emptied, when necessary, by lifting the hood stem 15 from the hole and tilting the trap upwards so that the trapped material falls out through the hood and hood stem.

The hose 18 is sufficiently long and flexible to permit locating the venturi ejector 8, from which the fine rock cuttings are discharged, at a convenient distance from the mouth of the drill hole. The ejector comprises a venturi tube 8 having a sharply constricted upstream portion leading to the throat of the tube and a gradually widened downstream portion leading away from the throat. As best shown in Fig. 3, a nozzle pipe 20 enters through the side of the ejector tube a short distance upstream from its throat. The lower end of the nozzle pipe 20 is closed, but it is provided with a nozzle orifice 21 in its side wall adjacent its lower end. The nozzle orifice is substantially coaxial with the bore of the venturi tube 8 and is aimed towards its throat. Compressed air at say 90 pounds per square inch is introduced through the nozzle pipe 20 and passes through the orifice 21 to operate the venturi tube 8 and create a suction which draws a stream of air-borne cuttings from the mouth of the drill hole through the hood 6 and the dust trap 7. It is desirable to provide the venturi tube 8 with a lining of rubber 22 to minimize wear due to the abrasive effect of the stream of rock dust being blown through it at high velocity.

Preferably the downstream side of the venturi tube 8 discharges into the dust collection chamber 9. A water spray nozzle 23 is mounted in the air stream at the discharge end of the venturi tube 8, so as to direct a spray of water into the stream of dusty air toward a series of closely spaced contactor plates. The main body portions 24 of the contactor plates are arranged parallel to the direction of flow of the air discharge from the venturi tube, but each plate is provided with a baffle portion 25 arranged at a substantial angle, preferably 90°, to the body portion. Each plate is arranged so that its baffle portion blocks off the passage between it and a neighboring plate, thereby requiring the air stream to undergo a sharp change in direction as it emerges from between the plates. The water spray delivered through the spray nozzle 23 together with fine rock cuttings and dust in the air stream impinge on the contactor plates and there unite to form a thin aqueous slurry which is discharged through the outlet 26 of the dust collector. The contactor plates divide the stream of dusty air into a series of narrow strips and are continuously covered with a film of water. They thus assure that maximum effectiveness of contact between the water and the rock dust is achieved. While use of the dust collecting chamber 9 is not essential, it is desirable to improve working conditions at the drilling site. If the impingement chamber 9 is not employed, owing to the lack of an adequate supply of water or for other reason, then care should be taken to place the discharge end of venturi tube 8 far enough to the leeward or downwind side of the drilling crew that no dust is blown towards them.

Eminently successful operation of the above-described embodiment of the invention has been achieved using a compressed air-operated venturi ejector capable of developing a partial vacuum equivalent to some forty-five inches of water. A suction of this magnitude was obtained through a drill hole three inches in diameter using a

venturi tube having an upstream internal diameter of three inches tapering uniformly to an internal throat diameter of one and seven-sixteenths inches in six inches, and then widening uniformly in eighteen inches to a downstream internal diameter of three inches. The orifice 21 in the wall of the nozzle pipe 20 of the venturi tube was one-quarter inch in diameter and one-quarter inch long, and compressed air was delivered to it at about 90 pounds per square inch gauge pressure.

Among the important advantages of the new dust removal apparatus is its simplicity and inexpensive construction. It eliminates dust quite completely from the immediate vicinity of the drill hole, and yet is easily portable and requires little or no attention while in operation. Use of the new apparatus in dry-drilling operations has led to increased drilling speeds, since the cuttings and dust may be withdrawn continuously from the bottom of the drill hole, instead of only intermittently as was necessary under former practice to minimize the dust hazard when using compressed air to blow out the cuttings.

We claim:

Apparatus for the removal of cuttings from a drill hole being dry-drilled in the earth comprising a hood adapted to overlie and enclose the mouth of said hole, said hood being apertured to permit passage therethrough of a drill rod extending substantially axially into said drill hole, an air pipe extending through said hood to a point adjacent the bottom of said drill hole, means for introducing compressed air into said drill hole through said air pipe, thereby to blow rock dust and cuttings up to and out of the mouth of said hole, a rock trap mounted in close proximity to said hood, said rock trap comprising a chamber of internal cross-sectional area that is large relative to the cross-sectional area of the drill hole, a conduit connecting the hood with the lower portion of the rock trap, a venturi ejector having a throat of reduced cross-sectional area relative to its inlet and outlet ends, a flexible conduit of small cross-sectional area relative to said rock trap connecting the inlet end of said ejector to the upper portion of the rock trap, said flexible conduit being out of alignment with the conduit connecting the hood with the lower portion of the rock trap, a compressed air nozzle pipe communicating with the interior of said venturi ejector upstream from and adjacent its throat, means for delivering compressed air through said nozzle pipe into said venturi ejector, whereby rock dust and fine cuttings blown up the drill hole by compressed air delivered through the air pipe are drawn through said trap and are discharged through said venturi ejector whereas relatively large cuttings and rock withdrawn from the drill hole in the air stream are collected in said rock trap, a series of closely spaced contactor plates mounted in the discharge of said suction ejector, said plates each having a body portion arranged parallel to the direction of flow of air discharged from the suction device and a baffle portion arranged at a substantial angle to said body portion, a spray nozzle mounted in the discharge from said venturi ejector upstream from the body portion of said plates, and means for delivering water to said nozzle, whereby water sprayed from said nozzle impinges on said plates and forms thereon a film of water in which fine cuttings drawn from the drill hole and discharged from the suction device are collected.
